UNITED STATES PATENT OFFICE

WILLIAM J. BAKER, OF NEWPORT, KENTUCKY

UTILITY FLASH-LIGHT

Application filed June 9, 1931. Serial No. 543,054.

This invention relates to a utility device consisting of a writing pad having an upright pivotally mounted flash-light attached thereto.

5 An object of the invention is to provide a device particularly adapted for use upon telephone stands for lighting the dial on a telephone and likewise the pad to which the light is attached.

10 Another object is to provide a device from which the flash-light portion may be removed and separately utilized.

Another object is to provide a device of the class described having a wide adjustability 15 in the directing of the light.

Another object is to provide a utility device of the kind described which is simple and efficient in use and manufacture.

These and other objects are attained by the 20 means described herein and set forth in the accompanying drawing, in which:

Fig. 1 is a perspective view of the utility writing pad and flash-light of the present invention;

25 Fig. 2 is a top plan view of the device with the pad and flash-light removed;

Fig. 3 is a fragmentary view of the bottom portion of the flash-light casing.

A common inconvenience in connection 30 with the operation of a dial telephone or with taking notes during a telephone conversation, is the fact that the telephone stand is frequently situated in a dark or dimly lighted corner of the room. Moreover it is frequently 35 undesirable such as in darkened halls or sick rooms and the like to turn on the ordinary electric light during use of the telephone. The device of this invention is particularly adapted to serve in circumstances of 40 the kind described.

The device comprises a flat base 5, preferably metal, and having one of its upper corners formed with an extension 6. The remainder of the top edge of the base 5 may be turned over on itself to form the resilient flap 7 adapted to clamp a writing pad 8 against the base 5. A circular metal cup 9 is rotatably mounted upon the extension 6 by means of a metal stud 10 which likewise serves as 45 one of the battery contacts. A pair of studs

11 may be provided interiorly of the cup 9.

The cup 9 is adapted to hold a tubular battery casing 12. For this purpose the casing 12 is provided at its lower end with slots 13 adapted to receive snugly studs 13 inside of the cup 9. After such positioning the battery casing may be pivotally moved together with the cup 9, to a desired position. The top of the casing 12 has fixed thereon a cap 14 to which an upstanding lug 15 may be secured. The top portion of lug 15 may be doubled upon itself to provide a pair of ears 16 between which a flash-light bulb may be pivotally mounted.

The light bulb holder may consist of an 65 integral metal piece comprising the tubular portion 17, the arm portion 18 which is pivotally mounted as at 19 between the ears 16, and the convex downwardly directed portion 20 constituting a shade for the flash-light bulb 21. The stem 22 of the bulb 21 is held within and has its end 23 projecting rearwardly of the tubular portion 17. A copper finger or strip 24 extends outwardly of the metal cap 14 between suitable insulating strips 25. The outer end of strip 24 is turned upwardly at substantially right angles as at 26 so that when the light bulb mounting is pivotally moved downwardly, the end 23 of the stem contacts the strip 24 70 completing the lighting circuit. The inner end of the strip 24 constitutes the upper battery contact inside of the casing. Upward movement of the light bulb mounting results in a breaking of the light circuit. The light 75 may be directed downwardly upon the writing pad 8 or the casing 12 may be moved upon its pivotal axis and the light directed downwardly upon the dial of a telephone. Other similar uses of the device are obvious. 80

For occasions on which it is desired to use the flash-light for other purposes, a separate circular cup similar to the cup 9 may be provided so that when the casing 12 is removed from the pivotally mounted cup, the separate 85 cup may be placed thereon and the flash-light used for any desired purpose.

What is claimed is:

1. A combined writing pad and flash-light comprising a flat base having an extension at 100

the top thereof and an integral flap for clamping a writing pad to the base, a cup member rotatably mounted upon said extension by means of a battery contact stud, a battery casing removably mounted in snug relationship within said cup member, a cap closing the upper end of the casing, a battery terminal extension projecting outwardly of the cap, an upstanding lug secured upon the cap, and a light directing holder pivotally mounted upon said lug and adapted to hold a light bulb with the stem thereof extending outwardly of the holder whereby pivotal upward and downward movement of the holder respectively breaks and effects contact of the light bulb stem with said outwardly-projecting battery terminal extension.

2. A combined writing pad and flash-light comprising a base, means for clamping a writing pad to the base, a cup member rotatably mounted upon the base by means of a battery contact stud, a battery casing removably mounted in snug relationship within said cup member, a battery terminal projecting outwardly of the top of the casing, an electric light bulb, and a pivotal mounting adapted to hold the bulb with the end of the stem exposed whereby the stem may be moved into and out of contact with said projecting battery terminal.

In testimony whereof, I have hereunto subscribed my name this 5th day of June, 1931.

WILLIAM J. BAKER.
